WINDOW SILL

Filed Sept. 18, 1929

FIG. 3

INVENTOR

William Van ALEN
BY
Jacobs & Schlesinger

ATTORNEY

UNITED STATES PATENT OFFICE

WILLIAM VAN ALEN, OF BROOKLYN, NEW YORK

WINDOW SILL

Application filed September 18, 1929. Serial No. 393,365.

The present invention relates to window sills and is more particularly directed toward a metal window sill adapted for use in brick buildings.

5 In building construction, window sills may be made out of the brick employed as the facing of a building. Such window sills are inexpensive but are objectionable because the joints are exposed to the weather. As these 10 parts of the building are exposed at all times, there is the maximum opportunity for water and frost to get into the joints, soften and disintegrate the cement and mortar employed, thus gradually washing it away and 15 weakening the structure, and possibly permitting water to get to the inside of the wall.

The present invention contemplates a metal window sill, preferably in the form of a strip of non-corrosive metal such as aluminum, 20 which is built into the building during its construction and which covers the joints in the brick, thereby preventing the weathering of the joints. The metal window sill contemplated in the present invention is placed 25 in position by the bricklayers during the construction of the building and is securely held in place by the brick and mortar. It overlies the brick and is adapted to receive the drainage 30 from the sub-sill of the window frame and is preferably provided with a drip to carry the water away from the wall so as to prevent staining the brick work of the walls below.

35 The accompanying drawings show, for purposes of illustrating the present invention, one of the many possible embodiments in which it may take form, it being understood that the drawings are illustrative of the invention rather than limiting the same.

40 In these drawings:

Figure 1 is a front, elevational view of the lower part of a window opening showing the improved sill in place.

45 Figure 2 is a vertical, sectional view on the line 2-2 of Figure 1 looking in the direction of the arrows, and

Figure 3 is a horizontal, sectional view taken on the line 3-3 of Figure 1.

50 As shown in the drawings, the improved window sill is indicated at 10. It is, for con-

venience, illustrated as being employed in a window opening provided with a more or less conventional window frame. The sub-sill of the window frame is indicated at 11, the stile at 12, the lower sash at 13, and the 55 upper sash at 14.

In constructing the building the face brick may be laid in any desired manner according to the design. They are here shown as being placed vertically, or on end, as indicated 60 at 15. These brick will, of course, be separated by mortar joints 16. Behind the brick, the wall may consist of tile or brick, as indicated at 17. The brick 15 and tile 17 will form the floor of the window opening. The 65 side walls of the window opening are indicated as being made up of brick 18, 18.

The metal window sill 10 preferably consists of a straight strip of extruded aluminum alloy, although a rolled section may be employed if desired. This strip has a sill-forming portion 20, an upwardly extending rear flanged portion 21, and downwardly extending front flanged portion 22, preferably provided with a drip or drain 23 spaced from 75 the front face of the brick wall.

In placing the window sill in the wall, the bricklayer lays the course of brick corresponding with those indicated at 15. He then places the mortar or cement on top of these brick 80 and places the metal window sill on this cement with the downwardly extending flange 22 against the front face of the brick already in place.

The metal window sill is mounted so that 85 it drains the water outwardly, as indicated in drawings, and the total depth of the window sill, when in this oblique position, is equal to the space A, occupied by the joint.

The width of the sill-forming strip is such 90 that the upwardly extending rear flange 21 is in line with the joint B behind the brick 18. This flange, as clearly indicated in Figure 3, comes behind this course of brick, and, as the 95 vertical space occupied by the window sill equals the thickness of the mortar joint, it will be apparent that the brick 18 may be placed in the same position as they would be were there no metal window sill. At the 100 same time this arrangement provides for in-

terlocking the metal sill so that it cannot move. Instead of using cement underneath the window sill, one can use caulking. The cement or caulking material is indicated at 5 24.

The window opening is then completed by the bricklayer in the usual manner. When the window frame is inserted in place, the sub-sill 11 extends over the top of the metal 10 sill 10 and may be downwardly flanged, as indicated at 25. Caulking material 26 is forced in underneath the sub-sill and against the flange 21 of the metal sill so as to prevent water from entering underneath the sub-sill. 15 Caulking material 27 is placed along the stile 12 of the window frame, and will prevent water from passing into the side joints.

It will be obvious from the foregoing that the metal window sill may be inserted in place by the bricklayers during the construction of the building and that, when placed in position, it will provide a permanent cover for the joints which would otherwise be exposed. This makes it possible to avoid the 20 use of more expensive stone or terra cotta window sills. The improved sill receives all the drainage from the window and carries it out beyond the face of the brick, allowing it to drain from the drip 23. This drip is arranged so that the water will tend to flow 25 away from the wall, thereby avoiding staining the wall.

What is claimed is:

1. A metal window sill section in the form 35 of a strip of uniform cross section and indeterminate length, the section being of Z-shaped cross section to present a narrow depending front flange for protecting the front face of a building wall, a narrow upstanding rear flange, and a substantially flat sill forming portion interconnecting the flanges.

2. A metal window sill section in the form 40 of a strip of uniform cross section and indeterminate length, the section being of Z-shaped cross section to present a narrow depending front flange for protecting the front face of a building wall, a narrow upstanding rear flange, and a substantially flat sill forming portion interconnecting the flanges, the 45 angular relation of the sill forming portion to the flanges being such as to provide a slight downward and outward pitch when the flanges are vertical.

50 Signed at New York city, in the county of New York and State of New York, this 14th day of September, 1929.

WILLIAM VAN ALEN.
